Application May 16, 1939, Serial No. 274,065
In Luxembourg May 18, 1938

13 Claims. (CL 115—35)

The present invention relates to machines having pusher or puller propellers and it is more especially, although not exclusively, concerned, among these machines, with boats of this kind and especially speed boats.

The chief object of the present invention is to provide a machine of the type above referred to which is better adapted to meet the requirements of practice than those existing up to the present time.

According to an essential feature of the present invention, the machine includes at least one group of two propellers respectively adapted to pivot about corresponding axes located symmetrically with respect to each other on either side of the median plane of the machine, and I provide means for simultaneously pivoting both of these propellers about their respective axes in opposite directions, and means for simultaneously pivoting both of these propellers about their respective axes in the same direction, these means being adapted to work simultaneously so as to permit of combining these displacements of the propellers.

Other features of the present invention will result from the following detailed description of some specific embodiments thereof.

Preferred embodiments of the present invention will be hereinafter described, with reference to the accompanying drawings, given merely by way of example, and in which:

Fig. 1 diagrammatically shows, partly in section, a propelling system for a motor boat made according to an embodiment of the present invention;

Fig. 2 is a diagrammatical view of a device for controlling this propelling system according to a first embodiment;

Fig. 3 is a diagrammatical view of another embodiment of the control device;

Fig. 4 is a diagrammatical view of still another embodiment;

Fig. 5 is a diagrammatical elevation view, partly in section, of a second embodiment of the propelling system according to the invention.

In the following description with reference to the drawings, it will be assumed that the invention is applied to a motor boat, such for instance as a speed boat.

The hull of this boat is made in any suitable manner.

I provide, for propelling this hull, at least one group of two screw propellers 1 and 1', which are symmetrically disposed on either side of the median plane of the boat and each of which is

mounted in a propeller bearing capable of pivoting about an axis, preferably vertical, whereby the shafts of said propellers can be turned both in the same direction about their respective axes, 5 by means of a suitable steering system, which permits of controlling the direction in which the boat is moving, these propellers being, for instance, moved respectively by motors 2 and 2' which are operative for their steering displacement.

According to the present invention, I provide, in cooperation with screw propellers 1 and 1', in addition to the steering system above referred to, means, independent of said steering system, 15 for imparting conjugated pivoting displacements in opposite directions to the supports of said screw propellers, whereby it is, for instance, possible to vary the magnitude of the propelling efforts resultant, and, in particular, by rotating 20 the propeller supports through 180°, to reverse said resultant and, consequently, the direction in which the boat is moving.

It will be readily understood that the provision of such means will greatly facilitate the handling 25 of the boat since it permits, while keeping the rate of working of the boat motor,

a. Either of reducing the speed, by pivoting the propeller supports through an angle ranging from 0 to 90°, a rotation through 90° corresponding to the neutral position, since the resultant of the propelling efforts is equal to zero in this position of the screw propellers;

b. Or of braking the boat by pivoting the propeller supports about their respective axes 35 through angles greater than 90°;

c. Or, again, of reversing nearly instantaneously the direction in which the boat is moving by pivoting the propeller supports through respective angles of 180°, this position being particularly interesting, especially in the case of 40 motor boats intended to undergo sudden changes of direction.

For this purpose, concerning first the system for simultaneously turning both of the axes of the propellers in the same direction, it is devised in such manner that it includes a steering control element 3 connected to said propellers 1 and 1' through the intermediary of a mechanism which is adapted to impart to the supports of said propellers, through means which will be hereinafter more fully described, pivoting displacements independent of the pivoting displacements of said supports in opposed direction.

For instance, I make use of the arrangement disclosed by Fig. 1:

In this embodiment of the invention, the steering control member 3 is constituted by a kind of hand-wheel adapted to coact, through the medium of pinions 4 and 5, with a transverse shaft 6 at the respective ends of which I provide differential gears D and D', identical to each other, the casings of these differential gears being mounted in such manner that they can turn coaxially in the frame 7 of the whole.

I key one of the pinions 8 of each differential gear on said shaft 6, while I couple the other pinion 9 of said differential (which pinion is connected to the above mentioned one through planet wheels 10), for instance through the medium of a shaft 11 or 11', of an endless screw 12 or 12', and of a helical wheel or worm wheel 13 or 13', to the support of the corresponding propeller support 1 or 1'.

With such an arrangement, when steering wheel 3 is operated, with a view to modifying the direction in which the boat is running, shafts 11 and 11' are rotated, in the same direction and at the same speed, if it is supposed that the casings of differential gears D and D' are then stationary. The axes of screw propellers 1 and 1' are then turned simultaneously in the same direction, and the desired modification of the direction of the efforts of said propeller screws is thus obtained.

Concerning now the above mentioned means for simultaneously turning both of the propeller screws in opposed directions, they are made in such manner that it is possible, through the action of an auxiliary motor, such for instance as electric motor 14, to turn in opposite directions the casings of differential gears D and D'.

For this purpose, said motor 14 drives, through an intermediate shaft 15, an endless screw 16, and a worm wheel 17 cooperating with said screw, a bevel pinion 18.

This pinion 18 meshes, on opposite sides, with two other bevel pinions 19 and 19', coaxial with each other and respectively rigid with pinions 20 and 20'. These pinions 20 and 20' themselves mesh with tooth wheels 21 and 21' themselves rigid with the casings of the respective differential gears D and D'.

In this way, when motor 14 is working, shafts 11 and 11', and therefore the supports of propellers 1 and 1', are given rotary movements in opposite directions.

In order to control this motor 14, I may have recourse, for instance, to a device permitting of starting said motor in the desired direction and of stopping it at will, according to the arrangement disclosed by Fig. 2.

In this embodiment, motor 14 is made in such manner that it runs in one direction or the other according as it is fed with current through one or the other of two conductors respectively designated by reference characters AV and AR, the first corresponding to the direction of rotation of the motor for which the propeller supports are brought into the position corresponding to the boat running in the forward direction, while the other corresponds to the direction of rotation of the motor for which the propeller supports are brought into the position corresponding to the boat running in the rearward direction.

I provide, respectively on each of said conductors, circuit breakers i_1 and i_2 , a contactor C being provided which permits either of sending at will the current into one or the other of said conductors, or on the contrary of leaving both of them unconnected, when in neutral position.

Preferably I provide a mechanism capable of automatically stopping motor 14 in the extreme position of the propeller supports. This mechanism may for instance include a threaded portion 5 of the shaft 15 of the motor, a longitudinally movable member 26 screwed on said threaded portion, and fingers 33₁ and 33₂ capable of occupying, for the extreme positions of said member 26 on which they are fixed, which extreme positions correspond to the extreme angular positions of the propeller supports, the opening of that of circuit breakers i_1 or i_2 which is in service.

With such an arrangement, the pilot will be able, through contactor C, to start motor 14 in one direction or the other and, in all cases, the motor will automatically stop when the propeller supports reach either of their extreme positions.

According to another embodiment, illustrated by Fig. 3, motor 14 is controlled by means of a device which causes the propeller supports to occupy a position corresponding to that given to a control member such as a lever 34, adapted to be locked in any desired position along a toothed sector 34'.

In this embodiment, conductors AV and AR 25 are respectively connected to contacts 35₁ and 35₂ located opposite each other and carried by a piece 36 adapted to slide along a rod 37 coupled with lever 34, this piece 36 being urged toward an intermediate position by two springs 38₁ and 38₂ acting in opposite directions.

On a threaded portion of shaft 15 (driven by the motor) I provide a runner 26 carrying a contact stud 39 located, with a sufficient clearance, between contacts 35₁ and 35₂ and adapted to close the AV circuit or the AR circuit according as it comes to touch one or the other of these contacts.

This control system will operate in the following manner:

40 All the parts are first supposed to be in the mean position illustrated by Fig. 3. According as lever 34 is displaced in one direction or the other, the AV or the AR circuit is closed. The motor is started, and, owing to the presence of springs 38₁ and 38₂, it is possible immediately to bring said lever 34 into any desired position ranging between the extreme positions thereof. That of these springs which is compressed maintains the corresponding contact against stud 39 until the displacement of runner 26 enables piece 36 to come back, under the action of the spring that was compressed when lever 34 was operated, into its mean position on rod 37. From this time on, any supplementary displacement of runner 26 causes the contact to be broken and stops the motor. Therefore the stopping of the motor is truly controlled by the position initially imparted to control lever 34.

Finally, it is possible, according to still another embodiment, to control motor 14 through a device which automatically ensures a rotation of 180° of the propeller supports.

This embodiment is illustrated by Fig. 4 and it is made as follows:

60 I provide, respectively on each of the conductors AV and AR, conductors 22₁ and 22₂ which cooperate with a control member such for instance as a push button (23₁ for conductor AV and 23₂ for conductor AR) which permits of closing the contact against the action of a spring 24₁ or 24₂.

For this purpose, two rods 40¹ and 40² are respectively connected to each push button. Rod 40¹ is provided with a notch 41¹ and rod 40² is provided with a notch 41².

The contactors 22¹ and 22² constitute the ends of arms 30¹ and 30², respectively pivoted to pieces 27¹ and 27². These pieces are slideable vertically in guiding members 42¹ and 42², respectively, which also serve to guide, but in the horizontal direction, rods 40¹ and 40².

The above mentioned pieces 27¹ and 27² are respectively provided with notches or slots 27a¹ and 27a² the upper edges of which are bevelled so as to form a tooth which coacts with the notches 41¹ and 41² of rods 40¹ and 40².

Fingers 43¹ and 43² fixed to each of the pieces 27¹ and 27² respectively, coact with a corresponding notch provided in arms 30¹ and 30², in such manner as to limit the angle existing between arm 30¹ or 30², on the one hand, and piece 27¹ or 27², respectively, on the other hand.

Finally, contactors 22¹ and 22² are subjected to the action of springs 28¹ and 28², which tend to apply them against the current feed studs 32¹ and 32², respectively, so as to close the circuits in which they are inserted.

In order to control contactors 22¹ and 22², I provide a runner 26 which is mounted on a threaded portion of shaft 15 and which includes inclined surfaces. These inclined surfaces cooperate, when the runner 26 comes into either of its extreme positions, with the lower ends of pieces 27¹ and 27². The distance between said pieces is chosen in such manner that the displacement of the runner between these extreme positions corresponds to a pivoting movement of 180° of the propeller supports.

Rods 40¹ and 40² are arranged in line with each other and their ends bear in an insulating piece 29a. Between the ends of rods 40¹ and 40², there is mounted an insulating piece 29 the length of which is chosen in such manner that when one of the push buttons is depressed inwardly, the other push button cannot be moved inwardly.

The device above described will work in the following manner:

If one of the two circuits, for instance circuit AV, is to be closed, the corresponding push button (23¹) is pushed inwardly, into the position shown by Fig. 4. The tooth formed by the upper edge of the slot provided in piece 27¹ is pushed into notch 41¹, under the action of spring 28¹. At the same time, contactor 22¹ is applied against contact 32¹. Circuit AV is now closed.

In the position illustrated by Fig. 4, push button 23¹ is locked in the depressed position, and the other push button, 23², cannot be moved inwardly as long as push button 23¹ is in this position.

When the AV circuit has just been closed, runner 26 was in the extreme position on the left hand side, close to piece 27². The working of the motor causes said runner 26 to come into the position on the right hand side as shown by Fig. 4. The number of revolutions of the motor shaft that is necessary for bringing member 26 from one extreme position to the other corresponds to what is necessary for pivoting the supports of propellers 1 and 1' through an angle of 180°.

A short time before it reaches its extreme position on the right hand side, runner 26 begins to act on piece 27¹, the inclined surface 25¹ of said runner lifting piece 27¹. At the beginning of the upward movement of piece 27¹, rod 40¹ is disengaged by tooth 41¹, whereby push button 23¹ can be returned into its position of rest by the action of spring 24¹. However, the beginning of the movement of piece 27¹ has not for its effect to disengage contact 22¹ from stud 32¹ because,

in view of the fact that lug 43¹ is free to move in the corresponding notch of arm 30¹, at the beginning of the upward movement of piece 27¹, arm 30¹ and contact 22¹ are driven by piece 27¹, against the action of spring 28¹, in order to break circuit AV, only when said lug 43¹ has reached the end of the corresponding notch provided in arm 30¹.

Therefore, push piece 23¹ is released from its locked position before the AV circuit is broken.

Then, the supports of propellers 1 and 1' can again be brought into positions at 180° from those they now occupy by acting on push button 23². The operation in this case is the same as that above described with reference to the action of push button 23¹.

Fig. 5 shows another embodiment of the system for driving the propeller supports.

In this embodiment, the supports of propellers 1 and 1' are also driven, through endless screws 12 and 12' and worm wheels 13 and 13', by shafts 11 and 11'. These shafts are rigid with worm wheels 9a and 9a', respectively. An electric motor 14a is supported by a frame 1a, adapted to pivot on supports 50 about an axis in line with the axes of shafts 11 and 11'. The shaft of this motor 14a carries, keyed thereon, a pinion 18 adapted to mesh with two pinions 19 and 19' journaled in frame 1a. These pinions 19 and 19' are rigid with endless screws 20a and 20a', coaxial therewith. These endless screws 20a and 20a' mesh with the above mentioned worm wheels 9a and 9a'. It should be noted that one of these endless screws is on one side of the corresponding worm wheel while the other is on the opposite side of the other worm wheel. For instance, as shown by the drawings, endless screw 20a is behind the vertical plane of the drawings, while endless screw 20a' is in front of said plane.

Frame 1a carried a sleeve 51 fitted with pinions 52 meshing with a chain 53 driven by the steering wheel 3.

The device above described will work in the following manner:

Supposing that motor 14a is not running, a rotation of steering wheel 3 will produce, through chain 53, pinions 52 and sleeve 51, a rotation of the motor frame 1a about the common axis of shafts 11 and 11'. The whole of the structure carried by said frame will pivot about said axis. Through worm wheels 9a and 9a' this movement will be transmitted to shafts 11 and 11' which will turn both in the same direction.

On the other hand, if motor 14a is caused to turn in one direction or the other, it drives pinions 19 and 19' both in the same direction, and this causes shafts 11 and 11' to be driven in opposite direction, due to the above noted location of endless screws 20a and 20a' on opposite sides of the corresponding worm wheels 9a and 9a', respectively. This causes the supports of propellers 1 and 1' to be turned in opposed directions simultaneously.

In the embodiment of Fig. 5, the control of the working of motor 14 is obtained through a device analogous to that of Fig. 3, including a control lever 34 coupled with a sliding rod 37. This rod carries two contacts 35a¹ and 35a² mounted on springs 54¹ and 54² and cooperating with a contact stud 39 carried by a nut 26 mounted on a threaded portion of shaft 11'.

It will be readily understood that the elastic mounting of contacts 35a¹ and 35a² on rod 37 is exactly the equivalent of the mounting of contacts 35₁ and 35₂ on a sliding member 36 sub-

jected to the antagonistic actions of springs 38₁ and 38₂ in the embodiment of Fig. 3.

In a general manner, while I have, in the above description, disclosed what I deem to be practical and efficient embodiments of the present invention, it should be well understood that I do not wish to be limited thereto as there might be changes made in the arrangement, disposition and form of the parts without departing from the principle of the present invention as comprehended within the scope of the appended claims.

What I claim is:

1. A machine which comprises, in combination, at least one group of two propellers respectively adapted to pivot about corresponding axes located symmetrically with respect to each other on either side of the median plane of said machine, two differential gears including each a casing journalled with respect to said machine, and at least two sun wheels and a planet wheel journalled in said casing and cooperating together, mechanical means coupling one of said sun wheels with one of said propellers for causing said last mentioned propeller to turn about its axis above mentioned when said last mentioned sun wheel is rotated with respect to said machine, control means for simultaneously rotating the two other sun wheels of the respective differential gears, and control means for simultaneously rotating the two casings of the respective differential gears, one of said control means being adapted to drive the two elements it rotates both in the same direction and the other control means being adapted to drive the two elements it rotates in opposed directions.

2. A machine which comprises, in combination, at least one group of two propellers respectively adapted to pivot about respective pivoting axes transverse to their axes of revolution and located symmetrically with respect to each other on either side of the median plane of said machine, two differential gears including each a casing journalled with respect to said machine and at least two sun wheels and a planet wheel journalled in said casing and cooperating together, mechanical means coupling one of said sun wheels with one of said propellers, respectively, for causing each differential gear to drive the corresponding propeller by pivoting it about the corresponding pivoting axis when said last mentioned sun wheel is turned with respect to said machine, control means for simultaneously turning the two other sun wheels of the respective differential gears both in the same direction, and control means for simultaneously rotating the two casings of the respective differential gears in opposed directions.

3. A machine which comprises, in combination, at least one group of two propellers respectively adapted to turn about respective pivoting axes transverse to their axes of revolution and located symmetrically with respect to each other on either side of the median plane of said machine, a frame carried by said machine, two differential gears, associated with said two propellers, respectively, including each a casing journalled in said frame and at least two sun wheels and a planet wheel journalled in said casing and cooperating together, mechanical means coupling one sun wheel of each differential gear with the corresponding propeller for causing said propeller to turn about its pivoting axis when said last mentioned sun wheel is turned with respect to said frame, hand control means for simultane-

ously turning the two other sun wheels of the respective differential gears both in the same direction, an electric motor, means for connecting said motor with said differential gear casings adapted to turn said casings in opposite directions when said motor is running, and means for controlling said motor.

4. A machine which comprises, in combination, at least one group of two propellers respectively adapted to turn about respective pivoting axes transverse to their axes of revolution and located symmetrically with respect to each other on either side of the median plane of said machine, two shafts in line with each other journalled in said machine and connected with said propellers respectively so that rotation of each of said shafts causes the corresponding propeller to turn about its pivoting axis, a frame journalled in said machine about the same axis as said two shafts, a motor carried by said frame, transmission means between said motor and each of said shafts arranged in such manner that the working of said motor causes said shafts to turn in opposed directions about their common axis, these transmission means being such that rotation of said frame about said common axis causes both of said shafts to turn together with said frame both in the same direction, control means for rotating said frame, and control means for said motor.

5. A machine which comprises, in combination, at least one group of two propellers respectively adapted to turn about respective pivoting axes transverse to their axes of revolution and located symmetrically with respect to each other on either side of the median plane of said machine, two shafts in line with each other journalled in said machine and connected with said propellers respectively so that rotation of each of said shafts causes the corresponding propeller to turn about its pivoting axis, a frame journalled in said machine about the same axis as said two shafts, a motor carried by said frame, an endless screw and worm wheel transmission between said motor and each of said shafts arranged in such manner that said motor drives said respective shafts in opposed directions and that the rotation of the motor, together with the frame that carries it, about the common axis of these two shafts causes said shafts to turn together in the same direction, control means for rotating said frame, and means for controlling said motor.

6. A machine which comprises, in combination, at least one group of two propellers respectively adapted to turn about respective pivoting axes transverse to their axes of revolution and located symmetrically with respect to each other on either side of the median plane of said machine, mechanical means for turning each of said propellers about the corresponding pivoting axis, control means for simultaneously driving said two mechanical means in the same direction, an electric motor adapted to drive said mechanical means in opposite directions simultaneously, said electric motor being capable of running in opposite directions, means for controlling said electric motor, and means for automatically stopping said electric motor after a predetermined displacement thereof.

7. A machine which comprises, in combination, at least one group of two propellers respectively adapted to turn about respective pivoting axes transverse to their axes of revolution and located symmetrically with respect to each other on either side of the median plane of said machine, me-

chanical means for turning each of said propellers about the corresponding pivoting axis, control means for simultaneously driving said two mechanical means in the same direction, an electric motor adapted to drive said mechanical means in opposed directions simultaneously, means for controlling said electric motor, and means, operative by said motor, for automatically stopping it after a fixed number of revolutions in one direction or the other.

8. A machine which comprises, in combination, at least one group of two propellers respectively adapted to turn about respective pivoting axes transverse to their axes of revolution and located symmetrically with respect to each other on either side of the median plane of said machine, mechanical means for turning each of said propellers about the corresponding pivoting axis, control means for simultaneously driving said two mechanical means in the same direction, an electric motor adapted to drive said mechanical means in opposed directions simultaneously, means for starting said electric motor, in one direction or the other, and adjustable means for automatically stopping said electric motor after any desired number of revolutions in one direction or the other.

9. A machine which comprises, in combination, at least one group of two propellers respectively adapted to turn about respective pivoting axes transverse to their respective axes of revolution and located symmetrically with respect to each other on either side of the median plane of said machine, mechanical means for turning each of said propellers about the corresponding pivoting axis, control means for simultaneously driving said two mechanical means in the same direction, an electric motor adapted to drive said mechanical means in opposed directions simultaneously, and alternatively operated means for automatically starting and stopping said motor in one direction and the other a number of revolutions

corresponding exactly to the passage of each of said propellers from a given position with respect to its pivoting axis to another position making an angle of 180° therewith.

- 5 10. A vessel having two propeller mountings spaced apart from one another, respectively, and adapted to pivot about vertical axes located symmetrically with respect to each other on either side of the median plane of said vessel, means 15 comprising a pair of transverse, coaxial shafts each geared to one of said propeller mountings respectively whereby said propeller mountings are rotated about their vertical axes by movement of said shafts, a control element geared to said shafts to move the same whereby, upon operation of said control element, to pivot said propeller mountings about their respective vertical axes in the same direction, and a second control element independent of the first-named 20 control element and geared to said shafts to move the same whereby, upon operation of said second control element, to pivot said propeller mountings about their respective vertical axes in opposite directions.
- 25 11. A vessel as claimed in claim 10, the movements of said transverse shafts being movements of rotation about their common axis, the gearing between said shafts and said propeller mountings including an endless screw on each of said 30 shafts, and a pair of helicoidal wheels on said propeller mountings and in mesh with said screws.
- 35 12. A vessel as claimed in claim 10, said propeller mountings including a propeller and a motor, said propeller and motor being affixed to said mountings and being rotatable about said vertical axis therewith.
- 40 13. A vessel as claimed in claim 10, the first-named control element being manually operable, said second control element including a motor and switch means for controlling the same.

ETTORE BUGATTI.
